UNITED STATES PATENT OFFICE.

ERNEST A. GROSS, OF LAMOILLE, MINNESOTA.

DOOR-OPERATING MECHANISM.

1,299,830.

Specification of Letters Patent.

Patented Apr. 8, 1919.

Application filed December 4, 1916. Serial No. 265,261.

To all whom it may concern:

Be it known that I, ERNEST A. GROSS, a citizen of the United States, and a resident of Lamoille, in the county of Winona and State of Minnesota, have invented certain new and useful Improvements in Door-Operating Mechanism, of which the following is a specification:

This invention relates to a door operating mechanism, and more particularly to a mechanism designed for opening garage doors by a vehicle approaching the same and an object of the invention is to provide a mechanism which is comparatively simple in construction and may be operated by either one or both of the rear wheels of a motor or other vehicle for opening the door of a garage or other building, or for opening or opening a gate to permit the passage of the vehicle therethrough.

More specifically, the invention comprises the provision of a plurality of rollers, preferably corrugated, positioned in the approach to the door or gate and adapted to be engaged by one of the wheels of a vehicle for rotating the rollers, the rotary movement of which is transmitted to a gear which meshes with a rack carried by the door or gate structure whereby the door or gate will be moved into an open position by the rotation of the rollers.

Other objects of the invention will appear in the following detailed description, taken in connection with the accompanying drawings, forming a part of this specification, and in which drawings:

Fig. 1 is a top plan of the mechanism illustrating in dotted lines the position of the vehicle with respect thereto.

Fig. 2 is a fragmentary front elevation of the door or gate and illustrating in connection therewith the gear which operates or opens the door.

Fig. 3 is a vertical section through the device illustrating the rollers and a vehicle wheel engaging the same.

Fig. 4 is a partial plan and horizontal section of a modified form of the device showing the same applied for opening a pair of sliding doors in opposite direction.

Fig. 5 is a detail section of a hand lever employed in the door operating mechanism to manually operate the doors independently of operation of the rollers.

Fig. 6 is a vertical section on the line 6—6 of Fig. 1.

Referring more particularly to the drawings, 1 indicates a door or gate, or other suitable sliding closures for an entrance opening indicated by the letter A. The sliding closure 1 has a rack 2 attached to the lower edge of the same with the teeth of which a pinion 3 meshes. The pinion 3 is mounted upon a shaft 4 which extends outwardly from the sliding closure 1 and is rotatably supported by suitable bearings 5 and 5^a, which are placed in a suitable ditch or trench 6 and protected by a suitable cover plate 7. The shaft 4 is connected, by a telescoping connection indicated at 8 to a shaft 70 which aligns with the shaft 4.

The shaft 9 has beveled gears 18 and 14 mounted thereon and these beveled gears mesh with beveled gears 15 and 16 respectively. The beveled gear 15 is mounted upon a shaft 17 while a shaft 18 carries the beveled gear 16. The shafts 17 and 18 are disposed in parallel planes, and in spaced relation to each other, being rotatably supported by suitable bearings 19 carried by the housing structure 20 which is embedded in the ground so that the uppermost portions of the rollers 21 and 22 which are carried by the shafts 17 and 18 respectively will be practically flush with the surface of the ground as shown in Fig. 3 of the drawings.

The rollers 21 and 22 are preferably corrugated, and they are adapted to be engaged by one of the rear wheels indicated by the letter B, of a vehicle, preferably a motor vehicle, for rotating the rollers by the rotation of the wheel B to in turn impart rotation to the shaft 4 and consequently to the gear 3 which gear meshing with the rack 2 will slide the closure 1 into an open position and permit the passage of the vehicle through the opening A.

The shaft 4 is movable longitudinally, and the bearing 5^a which rotatably supports this shaft, and is nearest the sliding closure 1, slides within the trough 6 and has an angled arm 5^b pivotally connected thereto by means of a slot and pin connection 5^c. The angle lever or arm 5^b is pivotally supported as shown at 5^d and is connected by means of a link 5^e with a hand lever 5^f. The hand lever 5^f is positioned with the garage or building A and carries a dog mechanism 5^g.

which coacts with a quadrant 5^a for holding the lever 5^c in adjusted position. By operating the lever 5^c, the shaft 4 may be shifted longitudinally, to move the gear or pinion 3 out of mesh with the rack 2 to permit the closure 1 to be opened or closed without affecting rotation of the rollers 21 and 22.

A yieldable buffer 24 is provided for limiting the opening movement of the closure 1 and it is provided for engagement with a buffering plate 25 carried by the edge of the closure.

In Fig. 4 of the drawings, the device is illustrated and adapted for moving a pair of sliding closures in opposite directions, for permitting entrance through the opening. These closures are indicated by the numerals 1^a and 1^b and may be hung in any ordinary manner. The operating mechanism, of the preferred form, includes the shaft 4^a which is connected to the shaft 9^a which shaft 9^a is in turn connected to the rollers 21^a and 22^a for rotation by the rotation of the rollers to rotate the shaft 4^a and consequently move the closure 1^a into an open position. These closures 1^a and 1^b have racks upon their under edges the same as the rack 2 and the door or closure 1^a is opened by the rotation of the shaft 4^a through the medium of a gear identical with the gear 3. The shaft 4^a has a beveled gear 30 mounted thereon intermediate its ends which beveled gear meshes with a beveled gear 31 carried by a shaft 32 which extends transversely to the shaft 4^a and like the shaft 4^a is embedded in a suitable trench 33, and is protected by a closure plate, so as to permit the passage of a vehicle over the shaft without in any way mutilating or interfering with the operation of the shaft. A beveled gear 34 is mounted upon the end of the shaft 32 opposite to the end which carries the beveled gear 31 and the beveled gear 34 meshes with a beveled gear 35. The beveled gear 35 is carried by a shaft 36, 45 which is positioned parallel to the shaft 4^a, being rotatably supported by suitable bearings 37 and this shaft 36 is adapted to have a beveled gear, the hub of which is indicated by the numeral 38 upon its inner end which pinion is adapted to mesh with a rack upon the lower edge of the closure 1^b, whereby upon rotation of the shaft 36 the closure 1^b will be moved into an open position. It will be noted, that by the arrangement of the various beveled gears, the shaft 36 will be rotated in the opposite direction to the rotation of the shaft 4^a, and consequently the sliding closure 1^b will be moved away from the closure 1^a, during the rotation of the shaft 36.

Changes in details may be made without departing from the spirit of this invention, but:

I claim:

1. In a closure operating mechanism, the

combination with a sliding closure, of a rack 68 along the lower edge of said closure, a pair of parallel rollers, means connecting said rollers and said rack for opening the closure upon rotation of the rollers.

2. In a closure operating mechanism, the combination with a sliding closure, of a rack along the lower edge of said closure, a pair of parallel rollers, a shaft connected to said rollers for rotation by the rotation of the rollers, a gear upon said shaft and meshing with said rack to move said closure upon rotation of the rollers.

3. In a closure operating mechanism, the combination with a sliding closure, of a rack along the lower edge of said closure, a roller, 80 a shaft operatively connected to said roller, a second shaft, a telescoping connection between said first and second mentioned shafts, a gear carried by said second mentioned shaft and meshing with said rack for moving said closure upon rotation of said roller.

4. In a closure operating mechanism, the combination with a sliding closure, of a rack along the lower edge of said closure, a roller, a shaft operatively connected to said roller, 90 a second shaft, a telescoping connection between said first and second mentioned shafts, a gear carried by said second mentioned shaft and meshing with said rack for moving said closure upon rotation of said roller, 95 and a yieldable buffer for limiting the opening movement of said closure.

5. In a closure operating mechanism, the combination with a sliding closure, of a rack along the lower edge of said closure, a pair 100 of parallel corrugated rollers, a longitudinally shiftable shaft, means operatively connecting said rollers and said shaft, a second shaft, a telescopic connection between said second shaft and said first named shaft, a 105 gear carried by said second shaft and meshing with said rack for moving said closure upon rotation of said roller, and a hand lever connected to said first shaft to shift it to permit operation of said closure independently of said rollers.

6. In a closure operating mechanism, the combination with a pair of oppositely movable sliding closures, of racks along the lower edges of said closures, a plurality of 110 rollers, and means connecting said rollers and racks for moving said sliding closures in opposite directions upon rotation of the rollers.

7. In a closure operating mechanism, the combination with a pair of oppositely movable sliding closures, of racks along the lower edges of said closures, a plurality of parallel corrugated rollers, a shaft operatively connected to said rollers, a second shaft aligning with said first named shaft, a connection between said first and second named shafts, a gear carried by said second

named shaft for meshing engagement with the rack carried by one of said sliding closures, a transverse shaft operatively connected to said second named shaft, a relatively short shaft operatively connected to said transverse shaft, and a gear carried by said relatively short shaft for meshing engage-

ment with the rack carried by the other of said closures for moving it in a direction oppositely to the direction of movement of the first named closure upon rotation of the rollers.

ERNEST A. GROSS.
